UNITED STATES PATENT OFFICE.

OTTO HALLENSLEBEN, OF HILDEN, GERMANY.

WOVEN PILE FABRIC.

SPECIFICATION forming part of Letters Patent No. 655,076, dated July 31, 1900.

Application filed November 5, 1897. Serial No. 657,565. (No specimens.)

To all whom it may concern:

Be it known that I, OTTO HALLENSLEBEN, a subject of the King of Prussia, German Emperor, and a resident of Hilden, in the 5 Province of the Rhine, German Empire, have invented certain new and useful Improvements in Woven Pile Fabrics, of which the following is an exact specification.

My invention pertains to the manufacture 10 of double-pile fabrics, in which two fabrics are woven face to face and the pile warp-threads tied not only by the ground-web but also by a second web which engages the pile.

Hitherto in the bindings for pile fabrics in 15 which cover warp-threads and threads engaging the pile were employed a disadvantage has become manifest that the tufts of pile could be withdrawn or pulled out of the finished fabric.

20 The object of my invention is to obviate the above by causing the tufts of pile to be secured against withdrawal or pushing out of the back and also to insure that the pile-threads shall always maintain an upright position.

According to my invention in the formation of double-pile fabrics of the said kind I employ a ground-web and also a second web to engage or bind the tufts of pile. Especially when employing a pile binding in which each pick or thread of weft carries pile it is possible in the case of coarse fabrics—such as carpets, plushes, &c.—to easily pull the separate tufts of pile out of the fabric, and 35 some of the bindings now in use to counteract this objection have not entirely answered the purpose. In the present invention by employing a special binding or tying web I obviate not only this objection, but by the 40 special arrangement of this particular web over the ground-web the tufts of pile assume an upright position of a durable character.

In order to make my invention more clear, I refer to the accompanying drawings, in 45 which similar letters denote similar parts throughout the several views, and in which—

Figures 1 and 2 show the binding of fabric of this description, of which Fig. 1 is a longitudinal section through the fabric, and Fig. 50 2 a horizontal section on the line xx through the tufts of pile as shown in Fig. 1.
 e designates the coarse ground weft-threads

of the ground-web, of which every thread carries pile.

$b b'$ are the binder warps or threads of the 55 ground-web, the threads of which bind cross-wise one over and one under each weft-thread. With this ground-web the new binding or tying web forming the characteristic feature of my invention is connected by means of 60 the chain c , arranged above the same, said binding or tying web being formed by or consisting of the fine ground weft-threads f and the ground warp-threads $a a'$.

The tufts of pile d , which are held by means 65 of the coarse ground weft-threads e of the ground-web, are held or secured between two adjacent coarse ground weft-threads e for the purpose of avoiding the pulling out of the pile-threads. At the same time the tufts of 70 pile are so tied that the same are caused to receive and maintain a perfectly-upright position. It should also be remarked that the said second binding-web, above the pile tufts, is more closely woven than the ground-web. 75

In the drawings a taffet-binding—*i. e.*, a binding where every single thread binds cross-wise one under and one over each pick or thread of weft—is used for the new binding or tying web, said taffet-binding being more 80 especially suitable for binding the weft-threads. I wish it, however, to be understood that I could employ any other suitable binding for this purpose.

Having thus fully described the nature of 85 this invention, what I desire to secure by Letters Patent of the United States is—

In a pile fabric, the combination of coarse ground weft-threads $e e'$, pile-threads d secured between adjacent coarse weft-threads $e e'$, 90 binder-warps $b b'$ binding the ground weft-threads $e e'$, fine weft-threads f and warp-threads $a a'$ located above the ground weft-threads $e e'$ and forming a second tying-web, a chain c connecting the two webs, for the 95 purpose and substantially as set forth.

In testimony whereof I have signed this specification in the presence of two subscribing witnesses.

OTTO HALLENSLEBEN.
